UNITED STATES PATENT OFFICE.

EMIL ANDERSON, OF BROOKLYN, NEW YORK, ASSIGNOR TO THE UNIVERSAL TURBINE COMPANY, OF NEWARK, NEW JERSEY, A CORPORATION OF NEW JERSEY.

CONDENSER PUMP.

1,415,975.

Specification of Letters Patent. Patented May 16, 1922.

Application filed February 9, 1915, Serial No. 7,096. Renewed October 6, 1921. Serial No. 505,924.

To all whom it may concern:

Be it known that I, EMIL ANDERSON, a citizen of the United States of America, and a resident of Brooklyn, county of Kings, and State of New York, have invented certain new and useful Improvements in Condenser Pumps, of which the following is a specification, reference being had to the accompanying drawings, forming a part thereof.

10 My invention relates to improvements in condenser pumps and its object is to provide a simple and efficient self contained apparatus which comprises its own motor and which may be directly affixed to a condenser well.

15 The advantages of this invention will appear in the following specification in which I will describe an apparatus built according to the present invention, the novel features 20 of which will be set forth in appended claims.

Referring to the drawings—

Figure 1 is a side elevation of a condenser of ordinary construction with a pump made 25 according to my invention connected thereto. A part of the condenser is drawn in section to clearly show the way my novel apparatus is associated with it.

20 In Figure 2 the condenser well and my condenser pump are shown in sectional side elevation.

Figures 3, 4 and 5 are sectional plan views 30 of the apparatus the sections in these figures being taken respectively on the lines 3—3, 35 4—4 and 5—5 of Figure 2.

An enlarged sectional side elevation of a portion of the motor is shown in Figure 6 and a plan view of a part of the rotor ring is shown in Figure 7.

40 Certain details of construction are shown in Figure 8, this figure showing in sectional end elevation one of the thin corrugated rings of the rotor, the section being taken on the line 8—8 of Figure 7 and directly above 45 this sectional view is shown an edge view of one of the curved bucket spacers, this view also being taken on the line 8—8 of Figure 7.

A sectional side elevation of the pump 50 rotor is shown in Figure 9 and a part of the rotor ring is shown in plan view in Figure 10, the view in this case being taken on the line 10—10 of Figure 9.

Like parts are designated by the same reference characters in all of the figures.

My improved condenser pump may be utilized with any of the well known forms of condensers, such as, for example, that shown in Figure 1 which comprises a tank 15 having water-heads 16 and 16^a with an inlet 17 and an outlet 18, a plurality of pipes or tubes 19 connecting the water-heads, a steam inlet 20 and a hot well 21 which receives the condensed steam.

The hot well is shown on a larger scale 65 in Figure 2 and it is to this part of the condenser that my improved pump is attached. As clearly indicated in the drawings, the pump and its motor occupy a very small amount of space and since this apparatus is 70 also efficient in operation, it possesses decided advantages over those hitherto available for this service. The pump comprises a stationary frame 22 composed of two parts 23 and 24, a shaft 25, an engine or 75 driving rotor 26, and a pumping rotor 27, both rotors being affixed to the shaft 25.

The condenser well 21 has a hole 28 and the part 23 of the frame 22 has a hollow cylindrical projection 29 which extends 80 through the hole into the well and is held in position by a flange 30 which is bolted or otherwise secured to the well. Within the hollow cylindrical projection 29 is a sleeve valve 31 which is vertically adjustable and is automatically controlled by a lever 32 having a float 33 at one end. The lever 32 is pivoted at 34 upon an upwardly projecting ear 35 of a stationary tubular member 36, which is within the sleeve valve 90 31. The tubular member 36 is materially smaller than the sleeve valve, and is substantially coaxial therewith. It is supported by a spider 37 which overhangs the top of the sleeve valve and has supporting 95 legs 38 which extend to the bottom of the hot well.

The tubular member 36 has a flange 39 in its lower end which forms a part of a partition wall 40 within the frame 23. This 100 partition wall is interrupted by an annular opening 41 into which the annular rotor ring 27 of the pump extends.

Between the frame sections 23 and 24 is a partition wall 42 having a bearing 43 for 105 the shaft 25, another guide bearing 44 for the same shaft being provided in the frame section 24. A suspension bracket 45 supports a frictionless thrust bearing 46 of any suitable character, which carries the weight 110

of the shaft and of the rotating parts which are secured to it. The pump rotor 27 comprises a disc 47 having a hub 48 and the rotor ring 27 which is shown in detail in Figure 9 and comprises spaced rings 49, 50 and 51, one set of buckets 52 between the plates 49 and 50 and a second set of buckets 53 between the plates 50 and 51. The passages between the buckets 52 which are clearly shown in Figure 5, are sub-divided by rings 54 and the passages between the buckets 53 are sub-divided into a relatively large number of wavy passages by rings 55 having wavy sections. The buckets are built up of curved spacing plates (see Figure 8) interposed between the rings, and the rotor ring is bolted or otherwise secured to the disc 47.

The pump rotor extends axially through the opening 41 in the partition 40 so that the intermediate ring 50 fits closely into the opening and constitutes a continuation of the wall, filling the gap between the flange 39 and the outer portion of the wall.

As clearly shown in Figure 2 the pump rotor is disposed in the space between the partition wall 40 and the partition wall 42 near the upper end of the shaft 25.

Between the partition wall 42 and the bottom frame of section 24 is disposed the driving engine or motor which comprises a stationary member 56 having a nozzle section 57, and the rotor 26 which comprises a plate 58 having a hub 59 and a rotor ring 60 which is shown on a larger scale in Figures 6 and 7. This rotor ring is preferably formed in accordance with my co-pending application, Serial No. 724,516, filed October 8, 1912 and comprises a pair of spaced rings 61 having buckets 62 between them, the passages being sub-divided by rings 63 having wavy portions between buckets and the buckets being composed of curved spacers as in the pump.

Motive fluid is admitted through an inlet opening 64 into the nozzle section 57 and is discharged from the nozzle through the wavy passages between buckets 62, and finally is exhausted through the outlet opening 65.

The tubular member 36 is preferably provided with holes 70 about on the level of the bottom of the well 21 and extends upwardly above the top of the sleeve valve 31 and hence above the maximum level of water in the well. The sleeve valve has ear projections 71 and is connected to the lever 32 by a bail 72 which serves as a link to connect the parts. The lever 32 has a weight 73 at the opposite end from the float 33, which acts as a counter-weight and substantially balances the weight of the sleeve so that it is easily raised and lowered in response to variations in the level of the liquid in the well. The interior of the tubular

member 36 constitutes an air passage from which air is continually being exhausted by that part of the pump which is composed of the buckets 53 and the wavy plates 55. An annular passage 74 is provided between the tubular member 36 and the sleeve valve 31 through which liquid is conducted to the other section of the pump comprised of the buckets 52.

As already explained, the passages between these buckets are sub-divided by the rings 54 and the arrangement of parts is such that one or more of these passages may be opened and closed by the automatic adjustment of the sleeve valve 31. The level of the water in the well may thus be prevented from becoming so low as to permit air to flow backwardly through the water outlet while it is, at the same time, prevented from rising beyond a certain maximum by reason of the activity of the pump.

It is thus evident that the pump in operation serves the double purpose of exhausting the air from the condenser and of draining the water from the condenser well.

The pump preferably operates at a high speed and the engine or motor which is shown as attached to it, is well calculated to perform this function and to drive the pump at such speeds as to render the operation of the entire apparatus highly efficient.

Secured to the shaft 25 below the bearing 44 is a worm wheel 75 which meshes with a worm gear 76 on a governor shaft 77, a governor of any well known form, such as, for example, a fly ball governor 78, is mounted on the governor shaft and is adapted to close a throttle valve 79 if the speed of the engine and pump exceeds a predetermined value. The holes 70 in the tubular member 36 may be larger or smaller dependent upon the desired amount of moisture preferably supplied to the air and forced outwardly through the wavy passages between the buckets 53. The apparatus is, of course, operative if there are no holes in the sleeve but the vacuum attainable is not as high as that which may be secured in the condenser by permitting a certain amount of water to be mixed with the air as it is pumped out.

Of course, the quantity of water may be increased indefinitely, and in fact all of the water from the well may pass directly into the tubular member 36 and be forced out through the wavy passages with the air. The sleeve 31 would then be superfluous and could be entirely omitted, but with this arrangement the power required to drive the pump is very materially increased, and consequently I prefer to utilize the structure illustrated in which the bulk of the water is forced out through the straight passages between the buckets 52 only a small amount of moisture being carried with the

air through the wavy passages between the buckets 53.

The water which is discharged from the pump outlet 80 is warm and may be supplied to the boilers of the system of which the condenser forms a part. The steam discharged through the passage 65 is preferably mixed with the water from the passage 80 in order to condense the steam and transfer its heat to the water. The moist air discharged from the air passage 81 will be permitted to escape into the atmosphere.

The operation of the apparatus will be clearly understood from the foregoing description, and will now be outlined as follows: Assuming that the driving engine is operating at a high speed and is driving the pump at a corresponding speed, if the level of the water in the well is as indicated in Figure 2, it will gradually flow over the top of the sleeve valve 31 filling the passage 74 and will be thrown out by the centrifugal pumping action of the buckets 52. As the level of the water in the well falls, the float 33 will move downwardly carrying the lever 32 and the sleeve valve 31 with it, hence water will be continuously supplied to the passage 74 and to the pump until the water level in the well becomes relatively low. Then the lower end of the sleeve valve 31 will have moved downwardly so as to close one or more of the passages between the plates 54 thereby reducing the capacity of the water pump, and if the condenser is assumed to be continuously in service, the water in the well will increase and cause the sleeve valve to again be raised. Thus the amount of water delivered by the pump is automatically determined by the amount of water in the well up to the full capacity of the pump which is designed to take care of the maximum condensation in the condenser.

At the same time the air is drawn through the tubular member 36 and is forced outwardly through the wavy passages between the plates 55.

The structure illustrated may be modified in various ways without departing from the spirit and scope of my invention and I intend that only such limitations be imposed as are indicated in the appended claims.

What I claim is:

1. A condenser pump comprising a casing divided into compartments and having a cylindrical projection adapted to extend through an opening into a condenser well, a sleeve movably mounted in the cylindrical projection, a rotary pumping element within the casing having independent circumferential air and water passages, and means for automatically adjusting the position of the sleeve to adjust the capacity of the water passage.

2. A condenser pump comprising a rotary pumping element having a water section and

an independent air section, a plate separating said sections and means including said plate for providing an independent annular water passage from the condenser well to and through the water section of the pump.

3. A condenser pump comprising a frame adapted to be secured to the condenser well and having a hollow projection extending into the bottom of the well, means within the hollow projection for providing independent air and water passages from the condenser to the pump and a rotary pumping element having a water section and an independent air section, a plate separating the sections, said sections being respectively adapted to receive water and air from said passages.

4. A condenser pump comprising a frame adapted to be secured to the condenser well and having a hollow projection extending into the bottom of the well, a stationary tubular member within the hollow projection extending above the liquid level in the well and forming an annular liquid passage and a tubular air passage from the condenser to the pump, and a rotary pumping element having a water section and an air section respectively adapted to receive water and air from said passages.

5. A condenser pump comprising a frame adapted to be secured to the condenser well and having a hollow projection extending into the bottom of the well, means within the hollow projection for providing independent air and water passages from the condenser to the pump, a rotary pumping element having a water section and an air section respectively adapted to receive water and air from said passages and means for driving the rotary element.

6. A condenser pump comprising a frame adapted to be secured to the condenser well and having a hollow projection extending into the bottom of the well, a stationary tubular member within the hollow projection extending above the liquid level in the well and forming an annular liquid passage and a tubular air passage from the condenser to the pump, and a rotary pumping element having a water section and an air section respectively adapted to receive water and air from said passages, and means for covering a portion of the water section to govern the capacity of the pump.

7. A condenser pump comprising a frame adapted to be secured to the condenser well and having a hollow projection extending into the bottom of the well, a stationary tubular member within the hollow projection extending above the liquid level in the well and forming an annular liquid passage and a tubular air passage from the condenser to the pump, and a rotary pumping element having a water section and an air section respectively adapted to receive water and air

- 4
- from said passages, an adjustable sleeve valve slidable in the hollow projection for covering a portion of the water section to govern the capacity of the pump.
5. 8. A pump rotor comprising a plurality of annular compartments, and ring shaped plates and interposed curved bucket spacers in each compartment, the plates of one compartment being corrugated between the bucket spacers to provide wavy passages.
9. A pump rotor comprising a disc having a hub and an axially extending peripheral rotor ring comprising a pair of independent compartments, ring shaped plates, interposed curved bucket spacers in each compartment, the plates of one compartment being corrugated to provide wavy passages between the bucket spacers.
10. A pump rotor comprising a disc having a hub and a peripheral rotor ring extending axially from the disc and comprising spaced rings forming a water compartment and an air compartment, ring shaped plates and curved bucket spacers in each compartment, the plates of the air compartment being relatively close together and corrugated to provide wavy passages between the bucket spacers.
11. A pump comprising a rotor having a disc provided with a hub and a peripheral rotor ring divided into a water compartment and an air compartment, a stationary tubular member coaxial with and extending within the rotor and having a flange spaced from the disc and cooperating with the rotor ring to separate the compartments thereof.
12. A pump comprising a rotor having a disc provided with a hub and a peripheral rotor ring divided into a water compartment and an air compartment, a stationary tubular member coaxial with the rotor and having a flange spaced from the disc and cooperating with the rotor ring to separate the compartments thereof and a frame or casting surrounding the tubular member and said rotor to form an annular inlet around the tubular member to one of the compartments and having a partition to provide independent outlets from said compartments.

In testimony whereof, I have hereunto set my hand this 1st day of February, 1915, in the presence of two subscribing witnesses.

EMIL ANDERSON.
